[57] CLAIM

The ornamental design for a utility cart, as shown and described.

DESCRIPTION

FIG. 1 is a top plan view of a utility cart showing my new design, it being understood that the handle has been broken away at two locations for ease of illustration.

FIG. 2 is a right side elevational view thereof, the left side being a mirror image of that shown.

FIG. 3 is a front end elevational view thereof, with the handle broken away for ease of illustration.

FIG. 4 is a rear end elevational view thereof, with the handle broken away for ease of illustration.

FIG. 1
